US0D1050157S

(12) **United States Design Patent** (10) Patent No.: **US D1,050,157 S**
Chou et al. (45) Date of Patent: ** Nov. 5, 2024

(54) **DISPLAY SCREEN OR PORTION THEREOF WITH GRAPHICAL USER INTERFACE**

(71) Applicants: **SHANGHAI MAGIMA DIGITAL INFORMATION CO., LTD.**, Shanghai (CN); **BIBO NETWORK, LLC.**, San Jose, CA (US)

(72) Inventors: **Jen-Chung Chou**, Shanghai (CN); **Qingyun Chen**, Shanghai (CN)

(**) Term: **15 Years**

(21) Appl. No.: **29/865,431**

(22) Filed: **Jul. 25, 2022**

(30) **Foreign Application Priority Data**

Jan. 27, 2022 (TW) 111300494

(51) LOC (14) Cl. **14-04**

(52) U.S. Cl.

USPC **D14/485**

(58) **Field of Classification Search**

USPC D14/489-495, 485-488

CPC G06F 3/048-04897; H04M 1/724-72484

See application file for complete search history.

Primary Examiner — Daniel J Domino

Assistant Examiner — Ana M. Vine

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
